UNITED STATES PATENT OFFICE.

GEORGE R. MEYERCORD, OF CHICAGO, ILLINOIS, ASSIGNOR TO HASKELITE MANUFACTURING CORPORATION, A CORPORATION OF NEW YORK.

METHOD OF AND APPARATUS FOR GLUING SHEETS EDGE TO EDGE.

1,397,489.

Specification of Letters Patent.

Patented Nov. 15, 1921.

Application filed May 8, 1920. Serial No. 379,770.

To all whom it may concern:

Be it known that I, GEORGE R. MEYERCORD, a citizen of the United States, residing at Chicago, county of Cook, State of Illinois, have invented a certain new and useful Improvement in Methods of and Apparatus for Gluing Sheets Edge to Edge, and declare the following to be a full, clear, and exact description of the same, such as will enable others skilled in the art to which it pertains to make and use the same, reference being had to the accompanying drawings, which form a part of this specification.

In making ply-wood sheets of any considerable size it is necessary to form each layer out of a plurality of pieces arranged edge to edge, the several layers, after being built up, being then laid upon each other and placed in the press. Because of the necessity of thus handling individual completed layers and in order to produce a satisfactory finished product, it is necessary that the abutting edges of the elements of each layer be effectively glued together.

Where the ply-wood is intended to be water-resistant, the glue joining the edges of the individual elements of each layer should be water-resistant. For rapidity of production the best glue for this purpose is that made of blood albumin which will set in a very short time under the influence of heat; it being sufficient, of course, that the heat be applied locally, that is simply in the vicinity of the joint which is being made.

The object of the present invention is to produce a simple and novel method of and machine for gluing together the abutting edges of two sheets, such as wood veneering, in such a manner that heat and pressure will be efficiently applied to the joint in order that the work may be done expeditiously and effectively.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a top plan view of a machine arranged in accordance with a preferred form of my invention:

Fig. 2 is a side elevation of the machine;

Fig. 3 is an end view, on a larger scale; 55

Fig. 4 is a transverse section on the same scale as Fig. 3, the parts being in the same positions as in Fig. 3;

Fig. 5 is a view similar to Fig. 4, the parts being shown in the positions which they occupy when the machine is closed on the work.

Fig. 6 is a section on an enlarged scale taken on line 6—6 of Fig. 3;

Fig. 7 is a transverse section through the upper heating element, on an enlarged scale;

Fig. 8 is a transverse section through a modified form of supporting platform or table;

Fig. 9 is a view similar to Fig. 7 showing a still further modification; and

Fig. 10 is a top plan view of a fragment of the table shown in Figs. 7 and 8.

Referring to Figs. 1 to 7 of the drawings, 75 1 and 2 represent two long flat bars lying parallel with each other and having their upper faces in the same horizontal plane. The members 1 and 2 lie above and are spaced apart from rigid supporting rails, 80 3; there being a series of coiled springs, 4, between each of the bars 1 and 2 and the corresponding supporting rail. In the arrangement shown, there are bolts, 5, fixed at their upper ends to the bars 1 and 2, each 85 bolt passing down through one of the springs and through the underlying supporting rail; there being a nut, 6, on the lower end of each bolt by means of which the springs are placed under an initial tension so that they will not yield and permit the bars to be depressed until a downward pressure of a predetermined strength is applied to the bars. The rails are supported at their ends by a suitable stationary frame 95 of which only parts of the two ends, 7, are shown. Across the tops of the bars 1 and 2 extends a plate, 8, preferably of comparatively thin sheet metal such as brass; this plate serving as the immediate supporting 100 surface for the work. Above the bars 1 and 2 are two rigid bars, 9 and 10, movably supported so that they can be shifted in the vertical direction and also from and toward each other. Underneath the plate between 105 the bars 1 and 2 is a heater, 11, there being

a similar heater, 12, lying between the bars 9 and 10. The heater, 12, is preferably supported by being hung from chains, 13, or the like, the upper ends of which are attached 5 to the tops of the bars 9 and 10. It is desirable that the bottoms of the bars 9 and 10 and the bottom of the heating element present a surface which is continuous to the extent that a piece of veneer or the like 10 slid underneath the same on the supporting plate, 8, be prevented from striking the side of the heating element or the inner face of one of the bars and be arrested thereby. This may conveniently be brought about 15 by making the heating element, 12, flat on the bottom and providing it with laterally-projecting fingers, 14, in the plane of the bottom; these fingers being long enough to enter notches or grooves, 15, in the bottom 20 faces of the bars 9 and 10. This arrangement permits the bars 9 and 10 to move toward each other without producing what might be termed a gap in the upper clamping 25 surface of the machine.

The bars 9 and 10 may be supported in any suitable way which will permit them to be moved downwardly and inwardly from their elevated positions. In the arrangement shown, each of the two movable bars 30 is supported at its ends by crank-like devices which, when turned through an angle of ninety degrees or less, shift the bars in both the vertical and the horizontal directions. As best shown in Fig. 6 there are 35 rotary studs or stub shafts, 16, journaled in and projecting through the end wall, 7, of the frame of the machine at the ends of the bars 9 and 10. On the inner end of each of the members 16, and eccentrically disposed with respect to the axis thereof, is a 40 projecting pin, 17, which enters a slot, 18, in the adjacent end of the corresponding bar; the slot being elongated transversely for a purpose to be hereinafter explained. On the 45 outer end of each of the members 16 is fixed an operating handle or lever, 19. The parts are so proportioned that when the operating levers are raised into the positions shown in Figs. 3 and 4, the bars 9 50 and 10 are held raised above the plate 8. When the operating levers are thrown outwardly and downwardly into the positions illustrated in Fig. 5, the movable bars are swung downwardly and toward each other. 55 In using the machine, it is first opened by raising all four of the operating levers, steam or any other heating medium being applied to the heating elements; two sheets of veneer or the like, whose edges are to be 60 glued together, are laid upon the supporting plate, 8, as indicated at A and B in Fig. 4, after glue has been applied to the two edges to be joined; and the operating levers are then swung down, causing the movable bars 65 and the upper heating element to be lowered upon the work, the bars being then moved toward each other so as to tend to move the two pieces of work into engagement with each other or, if they be in engagement, to press them tightly together. In laying the 70 two pieces of veneer in the machine the edges to be joined will usually be brought in contact with each other although it is not essential that this be done as long as both edges are brought underneath the upper 75 heating element and close enough together so that the subsequent action of the movable bars will move the two pieces of veneer far enough to close the gap between them. When the work has been clamped in the machine in 80 the manner explained, the surfaces to be glued together will be held in contact with each other under considerable pressure and, at the same time, heat will be applied locally, that is in the zone in which the joint occurs; 85 the result being a quick setting of the glue and an effective union of the two pieces of veneer.

The supporting plate, 8, is preferably made smooth while the bottom faces of the movable bars are preferably roughened slightly as indicated at 20, so that these bars will be capable of exerting a sufficient tractive effort on the sheets of veneer to induce the latter to slide on the supporting plate. The 90 grip on the veneer should not be so strong as to cause it to be crushed. Furthermore, there should be a uniform distribution of pressure throughout the entire length of the veneer and, in case the adjacent edges of 95 two sheets of veneer touch each other at some points and not at others, it should be possible for slippage to occur between the work and the gripping or clamping elements so as to permit gaps in the joint to be closed 100 after contact has been obtained between the two edges of the work at other points. All 105 these factors are taken care of by the spring underneath the bars 1 and 2 and the comparative flexibility of these bars due to their 110 thinness.

There is more or less of a tendency on the part of the movable clamping bars to adhere to the work and, if they were suddenly jerked from the clamping position into the release position, injury to the work might result. By causing the actuating and supporting pins, 17, for these bars to play in transversely-elongated slots instead of in simple round holes, there is a lost motion between 115 the actuating levers and the bars so that during the first part of the movement of these levers toward their release position, they do not influence the movable bars but simply release the pressure thereon and permit them to let go of the work simply by a raising of the forces left free to act when the restraining influence of the actuating levers is removed. This release of the grip 120 of the movable bars on the work may be 125 130

insured by means of the light leaf springs, 22, placed between the sides of the upper heating unit, 12, and the movable clamping bars which support the same; these springs

within the terms employed in the definitions of my invention constituting the appended claims.

I claim:

1. In a machine of the character described, 70 a flat work support yieldable in the downward direction under pressure, a clamping element for holding a sheet on said support, a second clamping element lying above said support, and actuating means 75 constructed and arranged to move the latter element up and down and simultaneously move it from and toward the first clamping element.

2. In a machine of the character described, 80 a work support having a heated zone, two parallel clamping bars lying above said support on opposite sides of said zone, a heating element loosely supported between said bars above said zone, and means for moving said 85 bars downwardly toward said support and laterally toward each other.

3. In a machine of the character described, 90 a vertical yieldable work support having a zone adapted to be heated, parallel clamping bars arranged above said support on opposite sides of said zone, a heater lying between and supported by said bars, and means for moving said bars from and toward each other and also from and toward said 95 support.

4. A machine of the character described which consists of two pairs of clamping devices, and means for closing said devices upon two sheets to be glued together and simultaneously moving them toward each other. 100

5. A machine of the character described which consists of a flat work support, a clamping element for holding the sheet on 105 the support, a second clamping element, and means for moving said second element toward said support and at the same time along the same toward the other clamp.

6. A machine of the character described 110 which consists of a flat work support, a clamping element for holding the sheet on the support, a second clamping element, means for moving said second element toward said support and at the same time 115 along the same toward the other clamp, and a heater between said clamping elements.

7. A machine of the character described comprising a yieldable support, a clamping element for holding a sheet on said support, 120 a second clamping element lying above said support, and actuating means constructed and arranged to move the latter element up and down and also from and toward the first clamping element. 125

8. A machine of the character described comprising a yieldable work support, a clamping element for holding a sheet on said support, a second clamping element lying above said support, actuating means con- 130

5 serving to hold the heating element in a central position and at the same time exerting a gentle pressure in a direction tending to spread the clamping bars apart.

10 The movable clamping bars are supported only by the pins which actuate them, in the arrangement shown, and therefore it is desirable to provide some means to hold them in proper relation to each other and the rest of the machine. This may conveniently be

15 accomplished by connecting the bars together by means of a link, 24, lying above the same and pivotally connected at its ends, as indicated at 25, 25, to the bars or to suitable ears or brackets, 27, fastened to the bars.

20 This device prevents the bars from tilting relatively to each other, but holds them upright and parallel with each other while permitting them to move from and toward each other.

25 It may sometimes be desirable to permit the lower supporting bars to move toward each other during the closing of the machine on the work. This may conveniently be accomplished, as illustrated in Fig. 8, by 30 mounting such bars, as indicated at 30 and 31, on the upper ends of spring rods or strips, 32, which bend under the influence of the diagonally-applied forces resulting from the downward and inward movement 35 of the upper bars. Or, if desired, the two bars, as indicated at 33 and 34 in Fig. 9, may be supported on the upper ends of swinging struts, 35, so arranged that the bars tend by gravity to swing downwardly and toward

40 each other; the bars being normally held in their raised positions by means of an intervening leaf spring, 36, which presses them upwardly and outwardly against suitable adjustable stops, 37. A simple downward 45 pressure on these bars will cause them to swing downwardly and toward each other. Where the lower bars are movable from and toward each other, the work-supporting plate must be made otherwise than in the

50 form of the machine illustrated in Figs. 1 to 7. The work-supporting plate may conveniently be made as illustrated in Fig. 10; being in the form of two plates, 38 and 39, having intercalated fingers, 40 and 41, which 55 maintain the continuity of the supporting surface while permitting the bars to which they are attached to move from and toward each other.

While I have illustrated and described 60 with particularity only a single preferred form of my invention, with a few simple modifications, I do not desire to be limited to the exact structural details thus illustrated and described; but intend to cover 65 all forms and arrangements which come

- structed and arranged to move the one of said clamping elements toward said support and also toward the other clamping element, and heating means in the zone between said 5 clamping elements.
9. A machine of the character described comprising a flat work support, a clamping element for holding a sheet on said support, a second clamping element lying above said 10 support, supporting cranks at the ends of said second clamping element, and means for turning said cranks so as to move the latter element up and down and also from and toward the first clamping element.
- 15 10. In a machine of the character described, two long flat parallel rails, springs beneath said rails for supporting the same, a heater arranged between and supported by the rails and having its upper surface flush 20 with the tops of the rails, two parallel clamping bars arranged above said rails, a heater lying between and loosely supported by said clamping bars and having a flat bottom adapted to extend downwardly at least 25 as far as the bottoms of the clamping bars,
- and means for moving said clamping bars from and toward each other and also from and toward said rails.
11. In a machine of the character described, two elongated parallel rails, springs 30 distributed along each rail underneath the same to support it, a comparatively thin metal plate resting on said rails, a heater on the under side of said plate between said rails, and coöperating clamping and heating 35 means arranged above said plate.
12. In a machine of the character described, two elongated parallel rails, springs distributed along each rail underneath the same to support it, a comparatively thin 40 metal plate resting on said rails, a heater on the under side of said plate between said rails, parallel clamping bars arranged above said plate, a heater suspended between said clamping bars, and means for moving said 45 clamping bars from and toward each other and also from and toward said plate.

In testimony whereof, I sign this specification.

GEORGE R. MEYERCORD.
